FLUE STRUCTURE FOR REGENERATIVE STOVES

Application filed August 10, 1928. Serial No. 298,790.

My invention relates to the type of regenerative heat exchange apparatus of which blast furnace hot blast stoves and open-hearth furnace regenerators are common forms. In apparatus of this type gases are burned and passed over or through some refractory material, such as fire brick. When this refractory material is sufficiently heated the flow of hot gas is shut off and cool air is forced through in the opposite direction. The air is heated by contact as it passes by the hot refractory material and continues to flow until a certain amount of the heat left in the refractory material by the hot gases is absorbed. The cycle is then repeated, the hot gases heating the refractory material and the cool air absorbing the heat, the refractory material being alternately heated by the hot gases and cooled by the air or gas whose temperature is to be increased.

In this specification and in the drawings I have shown and described my invention as applied to a common form of hot blast stove used in connection with blast furnaces for reducing iron ore to iron. In this type of stove the gases from the top of the blast furnace are conducted to the stove where they are burned, the hot burning gases passing by the refractory brick for a certain length of time. The gas is then shut off and air is forced through the heated checker-work of brick and into the blast furnace, furnishing the heated air required for the reduction of the ore. In this way the gas resulting from the operation of the blast furnace is utilized to pre-heat the air. Several separate hot-blast stoves are used in connection with one blast furnace so that while one is furnishing heated air to the furnace the others are being heated by burning waste gas from the blast furnace in the combustion chamber of the stove. In this way a continuous supply of pre-heated air is obtained. In case of an open hearth regenerator the waste heat from the furnace heats the regenerators directly (the open hearth furnace itself acting as a combustion chamber for the waste gases) and the reversals occur more frequently than in blast furnace practice.

Among the objects of my invention are:

The provision of an improved method of laying up brick for the flue structure of regenerative stoves by virtue of which each brick in the flue structure can expand without disturbing its neighbor; the provision of a flue structure made of rectangular brick in which the individual flues have a much greater surface area in proportion to their cross-section area than other forms which have been heretofore proposed; the provision of a checker-work structure made of rectangular brick which may be easily and quickly laid up and in which all joints between bricks are bonded by the bricks in the adjacent courses; the provision of a checker-brick structure in which there is no waste or inactive brick, the brick being so laid that the walls between all the flues are of uniform thickness, and the provision of a flue structure having flues cross-shaped on a plane perpendicular to their longitudinal axes. Other advantages of my invention over other types of flue structures will be evident from the drawings and specification.

I do not limit my invention to the specific form shown in this specification as it will be clear to those skilled in the art that it may be adapted to other types of regenerative heat exchange apparatus and embodied in structures other than that shown.

Referring to the drawings:

Fig. 1 is a vertical section through a common type of hot blast stove, the flues of which are built in accordance with my invention.

Fig. 2 is an enlarged view taken between lines 2A, 2A and 2B, 2B in Fig. 1, showing several courses of brick of a portion of the stove shown in Fig. 1.

Fig. 3 is a plan section of my improved stove taken on line 3—3 of Figs. 1 and 2.

Fig. 4 is an enlarged plan view of a portion of the flue structure showing two courses of brick.

Fig. 5 is a perspective view of two vertically adjacent courses of brick separated to show how the bricks of one course overlap those of the adjacent course.

The hot blast stove shown in Fig. 1 is the type used in connection with blast furnaces. When the stove is in operation the blast fur-

nace gas enters the bottom of the combustion chamber 1 through the pipe 2. The gas burns in the chamber 1 and the dome 3 and passes down through the refractory brick flues 4 and out the chimney 5. After the checker-brick flue structure is sufficiently heated the gas is shut off and air is passed through the stove in the opposite direction. It enters at the bottom and passes up through the heated flues 4, then down through the combustion chamber 1 and out at the bottom of the combustion chamber. The stove has a steel shell 6 and a lining 7 of refractory material. As shown in Figs. 3 and 4 the flues 4 made in accordance with my invention are cross-shaped in horizontal section. Flue structures which have been built prior to my invention have been of square, rectangular, or round shape in horizontal cross-section.

My invention provides a method for laying up cross-shaped flue structures from standard rectangular brick. As shown in Fig. 3 two sizes of brick are used. Bricks 9 may be considered to be 9" x 3" x 4" and bricks 10 to be 6" x 3" x 4". The bricks, of course, can be of any practical depth other than 4", and the other dimensions may be varied depending on thickness of flue wall and area of flue opening desired.

The alternate courses of brick in my flue structure are so laid that each joint between any two bricks of a course is bonded by a brick in the course above. In Fig. 3 two courses of my flue structures are shown. The lower course appears on the left and the upper course on the right. On the right the lower course is shown under the upper course in dotted lines. As will be seen from the drawings the lower course consists of double rows of 9" x 3" brick 9 laid parallel and 12" apart. The bricks in each single row of these double rows are spaced apart endwise three inches and the three-inch openings are bridged by the bricks in the adjacent single row of spaced-apart bricks. Between the double rows of spaced-apart 9" x 3" bricks 9 are laid the 6" x 3" bricks 10. These are placed with their longitudinal axes at 90° to the longitudinal axes of the double rows of 9" x 3" bricks 9 and are staggered so that each overlaps the adjacent brick three inches. These 6" x 3" bricks 10 form zig-zag rows between the spaced-apart double rows of 9" x 3" brick 9 and, as is clearly shown in Fig. 3, complete the walls between the cross-shaped flue openings 4. These cross-shaped flue openings 4 are all of the same size, each of their angles being 90° and each of their sides 8 being three inches long. They are arranged in diagonal rows and are so spaced apart that the center line 11, Fig. 4, of the bricks is always equidistant from the surface of two adjacent flue openings. Thus if each flue opening is considered to be surrounded by brick 1½" thick, there will be no part of

the refractory material which is so far from a flue surface that it is inefficient in absorbing and giving off heat. This is an important advantage of my invention as the regenerator is much more efficient when the bricks are all heated and cooled equally, and there is no inactive material. All the refractory material is utilized for heat transfer purposes and none acts as a mere support for some other part of the structure.

As will be seen by reference to Fig. 2, the plan section through the flues of Fig. 3 is taken through two vertically adjacent courses of brick, the right-hand portion showing the upper course and the left-hand portion being the lower course. The upper course is laid up in exactly the same way and of the same size bricks as the course below. However, in order that the joints between the bricks may be bonded and each brick not merely piled directly on top of the corresponding brick in the course below, the longitudinal double rows of 9" x 3" bricks 9 are laid on top of the 6" x 3" bricks 10 of the course below and midway between the double longitudinal rows of 9" x 3" bricks 9 of the course below. These double longitudinal rows of 9" x 3" bricks 10 are laid parallel in all the courses. In this way the cross-shaped flue openings of the upper course correspond with those of the lower course and each joint in the lower course is covered by a brick in the upper course.

Fig. 5 of the drawings shows two adjacent courses of brick in perspective. The courses have been separated to show the individual bricks more clearly. The method of laying up the bricks so that each course is bonded by the adjacent courses can be clearly seen. Several of the bricks in the upper course have been projected down to show where they would be placed on the lower course if the courses were not separated, for instance the bricks 9' would cover the shaded area 9^a and the bricks 10' would cover the shaded area 10^a.

The entire flue structure of the stove is built up as above described, as many courses being laid up as are necessary to give the length of flue desired. The alternate courses of bricks are identical and could be exactly superimposed upon each other, but this would not provide a bond between the different courses. The bonding which is very advantageous in strengthening the entire structure is obtained as above described and consists of merely shifting the position of every other course. All the courses when considered separately are identical.

My form of flue is superior to other forms in that it has a much greater surface area of brick in proportion to the cross-section area. This can be shown by assuming that the flues shown in Fig. 3 of the drawings are laid up of bricks three inches wide. It is evident that each of the surfaces 8 of the flues are

three inches long and the cross-section area of a flue is 45 square inches. If the bricks are four inches deep the surface area of a flue one brick high will be $3'' \times 4'' \times 12 = 144$ square inches.

6 A square flue having a cross-section area of 45 square inches would be approximately 6.7 inches on a side and the surface area of a section of flue one brick (4 inches) high would be $6.7'' \times 4'' \times 4 = 107.2$ square inches. From the above calculations it will be seen that my flue shape gives 36.8 square inches more surface in four inches of flue length than a square flue having exactly the same cross-section area. This is an increase of 34.3% over the square flue and is of great advantage in absorbing heat from the hot gases and allowing the cold air to absorb the heat from the brick.

20 Another important advantage of my invention over all previous flue structures is that there are no continuous rows of bricks butting against each other and causing distortion of the structure and cracking of the walls when the bricks expand and contract 25 when heated and cooled.

I do not limit my invention to the specific form shown or to any particular size of brick and it will be evident to those skilled in the art that bricks of other sizes, shapes and proportions than above described can be used to carry out my invention.

I claim:

1. In a regenerative stove, a flue structure having vertical flues, the walls of said flues being composed of rectangular brick laid up in courses one upon the other, said flues being cross-shaped on a plane perpendicular to their vertical axes and extending substantially the full height of the flue structure.

40 2. In a regenerative stove a flue structure having cross-shaped flues laid up of rectangular brick the alternate courses of which are identical and the intermediate courses offset so that the joints between the bricks of the 45 alternate courses are bonded by the bricks of the intermediate courses.

3. A flue structure having vertical flues, said flue structure being laid up of rectangular bricks and said flues being cross-shaped in horizontal cross-section, said rectangular bricks being laid in courses, said courses being so laid that the bricks of alternate courses could be exactly superimposed on each other and the bricks of the intermediate courses 55 between said alternate courses could also be exactly superimposed on each other, said alternate and intermediate courses being laid up in the same manner but offset relative to each other.

60 4. The method of laying up rectangular brick to form a flue structure having cross-shaped flues which consists of first laying one course of bricks, the individual bricks of which have certain positions relative to 65 each other, laying a second course of bricks

on said first named course, the individual bricks of said second course having the same positions relative to each other that the bricks of said first named course have but the entire second course being offset relative to said first course so that the flue openings of both courses will correspond and the bricks of said second course will bond the joints between the bricks of said first course, and continuing laying up alternate courses exactly corresponding to said first and second courses until the desired flue length is obtained.

70 5. A flue structure having flues cross-shaped on a plane perpendicular to their longitudinal axes composed of superimposed courses of rectangular bricks, the individual bricks of each course being placed so that they bond the joints between the individual bricks of the course below, said cross-shaped flues extending substantially the full height of the flue structure.

75 6. A flue structure having flues cross-shaped on a plane perpendicular to their longitudinal axes laid up of rectangular bricks in which each individual flue is surrounded by the same thickness of brick as surrounds every other flue in said structure, said cross-shaped flues extending substantially the full height of the flue structure.

80 7. A flue structure having cross-shaped flues laid up of rectangular bricks in which each brick is free from contact with other bricks on at least one end and is free from contact with other bricks on at least one-half of its total side surface.

85 8. The method of laying up flue structures having flues cross-shaped on a plane perpendicular to their longitudinal axes comprising spacing the bricks so that each brick can expand into a cross-shaped flue opening.

90 9. In a regenerative stove a flue structure having vertical flues, the walls of said flues being composed of rectangular brick laid up in courses one upon the other, said flues being cross-shaped on a plane perpendicular to their vertical axes, each course of brick consisting of parallel double rows of brick three units long and one unit wide, said parallel rows being composed of two adjacent single rows of brick laid end to end with one unit space between their ends and the bricks in each of the two single rows bridging said space between the ends of the brick in the adjacent row, said parallel double rows of brick being spaced apart four units, the space between said parallel double rows of brick being occupied by brick two units long and one unit wide, said two unit long bricks being laid so as to complete the walls of said cross-shaped flues.

100 10. A flue structure having vertical flues cross-shaped in horizontal cross-section laid up of superimposed courses of two sizes of rectangular bricks, both of said sizes of bricks

being of the same width and depth, but the smaller of said sizes of bricks being two-thirds as long as the larger of said sizes of bricks, each course being laid up of parallel, spaced 5 apart double rows of said larger bricks, the space between said parallel double rows being occupied by zig-zag rows of said smaller bricks placed with their longitudinal axes at ninety degrees to the longitudinal axes of 10 said larger bricks, said parallel double rows of said larger bricks being composed of two single rows of said larger bricks, each brick of each single row being spaced apart endwise a distance equal to the width of a brick, said 15 single rows being offset so that each brick of each single row bridges the space between the ends of the adjacent bricks in the adjacent single row, and each zig-zag row of smaller bricks being laid in so that a small brick butts 20 against the center of one side of each of said larger bricks which make up said parallel double rows and other small bricks lie midway between said spaced apart double rows of said larger bricks with one-half of each of their 25 opposite side surfaces adjacent the side surfaces of the adjacent smaller bricks which butt against said larger bricks.
